UNITED STATES PATENT OFFICE

2,363,835

FREQUENCY CONVERSION

Howard M. Crosby, Schenectady, N. Y., assignor to
General Electric Company, a corporation of
New York

Application April 1, 1943, Serial No. 431,445

4 Claims. (Cl. 250—39)

My invention relates to frequency conversion, and more particularly to balanced or push-pull frequency converters having signal means responsive to a deviation of the heterodyne frequency from a selected normal value.

Frequency mixers or converters are an integral part of superheterodyne receivers in which the incoming signal modulated radio frequency wave is mixed with a locally generated oscillation of different frequency to obtain a modulated wave of intermediate frequency. Such mixers are also used in transmitting apparatus to supply a carrier wave of desired frequency for modulation. In transmission of signals the use of a heterodyne converter for supplying a wave of carrier frequency has the advantage of flexibility over a simple crystal oscillator in that the frequency of the carrier wave may be varied over a range of selected values. Furthermore, if a crystal oscillator is used to supply one of the input oscillations to a heterodyne converter in a radio transmitter, the arrangement is superior to a simple vacuum tube oscillator in that an uncontrolled variation in the frequency of the vacuum tube input oscillator will produce, on a percentage basis, a smaller change in the difference or output frequency. Thus the combination in a mixer of a wave of fixed crystal frequency and a wave of variable vacuum tube oscillator frequency provides means for combining the flexibility of the vacuum tube oscillator, at least in part, with the constant frequency characteristic of the crystal oscillator.

In certain applications, however, absolute constancy of output frequency of such a converter is necessary. Such constant frequency output is always desirable in both a superheterodyne receiver and in the carrier wave generator of a transmitter, or wherever a frequency converter is used.

Accordingly, it is a general object of my invention to provide means for detecting a deviation from a desired normal value of the superheterodyne frequency in a frequency converter.

It is a further object of my invention to provide a new and improved balanced or push-pull frequency converter having means for detecting deviation of the heterodyne frequency from a desired normal value.

It is a specific object of my invention to provide a normally null signal means responsive to difference frequencies within both the audible and visual ranges and down to one cycle per second or less to indicate the extent of departure

of the heterodyne frequency of a frequency converter from a desired normal value.

My invention itself will be more fully understood and its objects and advantages better appreciated by referring now to the following detailed specification taken in conjunction with the accompanying drawings in which Fig. 1 is a schematic circuit diagram of a frequency converter embodying my invention; and Figs. 2 and 3 are graphical illustrations of certain conditions of operation of the circuit shown at Fig. 1.

Referring now to the drawings, and particularly to Fig. 1, I have chosen for the purpose of illustration to show my invention applied to the carrier wave generator of a radio transmitting apparatus. In the drawings a source 10 of electric oscillations of fixed frequency and a second source 11 of electric oscillations of a different frequency and subject to uncontrolled frequency variations jointly supply energy to the current control grids of a pair of push-pull converter or mixer tubes 12 and 13. The tubes 12 and 13 supply oscillating electric energy at the sum and difference frequencies to an output transformer 14. The source of oscillations 10 of fixed frequency may suitably comprise a piezoelectric crystal oscillator connected to supply oscillations at fixed frequency and in like phase to a pair of control grids 19 and 17 in the electric discharge tubes 12 and 13, respectively. The source 11 may be a vacuum tube oscillator of any well-known type the frequency of which is controllable, and any selected frequency of which is subject to slight uncontrolled variations. The source 11 is connected to supply electric oscillations in phase opposition to a pair of suppresser grids 19 and 20 in the electric discharge tubes 12 and 13, respectively. In the example chosen by way of illustration, namely, a frequency converter for supplying an unmodulated carrier wave to a transmitting apparatus, the oscillator 11 will supply an unmodulated wave to the grids 19 and 20 and the intermediate frequency output wave appearing at the transformer 14 will be supplied to a modulator where it may be modulated, either in amplitude or in frequency, at a signal frequency representative of the intelligence being transmitted. Preferably the frequency of the oscillator 10 is relatively high compared to the frequency of the oscillator 11. By way of example it will be assumed that the fixed frequency of the source 10 is ten times the desired normal frequency of source 11.

The electric discharge devices 12 and 13 are also provided with anodes 30 and 31 and cath-

odes 32 and 33, respectively. The anode and cathode of each discharge tube are connected in separate output circuits both of which are supplied from a common source of direct electric current supply such as a battery 34. The separate output circuits of the discharge tubes 12 and 13 are connected to the battery 34 in opposing or push-pull relation, and each includes one-half of the primary winding of the output transformer 14, one of the discharge tubes 12, 13, and one of a pair of similar resistors 35, 36. The positive terminal of the battery 34 is connected to the midtap of the primary winding of the transformer 14, while the negative terminal of the battery 34 is connected to the resistors 35 and 36. The discharge tubes 12 and 13 are also provided with screen grids 37 and 38, respectively, which are connected together and to an intermediate point on the battery 34 of positive potential with respect to the potential of the cathodes 32 and 33. The screen grids 37 and 38 serve electrostatically to isolate the control grids 16 and 17 from the suppresser grids 19 and 20, respectively.

The resistors 35 and 36 each have one end connected to the negative terminal of the battery 34 and to ground at 39. For the purpose of preventing the passage of relatively high frequency currents through the resistors 35 and 36, the resistors are shunted by high frequency by-pass condensers 40 and 41. The opposite ends of the resistors 35 and 36 are connected through high frequency choke coils 42 and 43 to a suitable signal frequency amplifier 44. The output of the signal amplifier 44 is supplied in parallel circuit relation to both a suitable audible signal reproducing device, such as a headphone 45, and to a visual signal receiving apparatus, such as an electric discharge tube 46. The discharge tube 46 is preferably a visual tuning indicator tube of the type described and claimed in Patent 2,051,189 issued to H. M. Wagner on August 18, 1936. Briefly, the tube 46 comprises an evacuated envelope containing a cathode 47, an anode 48, a control grid 49, and a target electrode 50. For indicating purposes a suitable source of direct current electric energy, such as a battery 51, has its positive terminal connected directly to the target electrode 50 and through a resistor 52 to the anode 48. The negative terminal of the battery 51 is connected to the cathode 47. The signal oscillation from the output of the amplifier 44 is connected between the cathode 47 and the control grid 49 of the tuning indicator tube 46. The target electrode 50 is in the form of a conical luminescent screen upon which is formed a circular image the circumferential length of which is directly proportional to the voltage between the cathode 47 and the control grid 49.

From the foregoing detailed description of the organization and arrangement of the apparatus, the operation of my invention will be understood from the following description. In the first place it will be readily apparent that the balanced or push-pull mixer circuit itself operates in a well known manner to beat the oscillations from the low frequency source 11 with the oscillations from the high frequency source 10 to supply output oscillations to the transformer 14 at the sum and difference frequencies. The transformer 14 is provided with a capacitor 53 tuned to resonance with the secondary winding of the transformer 14 for oscillations at the difference frequency, so that only these oscillations appear at the output. Substantially no voltage at the sum frequency

appears across the secondary winding of the transformer 14 because of the relatively low impedance which the tuned transformer circuit offers to oscillations at the sum frequency. It will also be noted that currents at the frequency of the source 10 do not appear in the secondary winding of the transformer 14 because of the fact that such currents flow in like phase relation and in opposite directions on opposite sides of the midtap of the primary winding of the transformer 14. Potentials at the frequency of the source 11, since they are supplied to the converter tubes 12 and 13 in opposing phase relation, induce potentials of like frequency in the secondary winding of the transformer 14. However, since the frequency of the source 11 is widely different from the difference frequency for which the output circuit of the transformer 14 is tuned, the impedance of the output circuit for currents of the frequency of the source 11 is very low and substantially no voltage of this frequency appears across the transformer secondary winding.

Let it now be assumed that there is present in the output of the vacuum tube oscillator 11 an appreciable amount of tenth harmonic oscillating energy. If then the frequency of the tube oscillator 11 is precisely one-tenth the fixed frequency of the crystal oscillator 10, which is the desired condition assumed, the tenth harmonic of the tube oscillator 11 will be of precisely the same frequency as the crystal oscillator output. The tenth harmonic of the source 11, as well as the fundamental oscillation from this source, will be mixed by the tubes 12 and 13 with the crystal output from the source 10 to provide sum and difference frequencies in the output circuits of each of the tubes. When the frequency of the source 11 is properly adjusted, the difference frequency between its tenth harmonic and the crystal frequency will be zero, so that a predetermined constant average direct current will be present in the output circuits of each of the mixer tubes 12 and 13. The sum frequency of the crystal and the tenth harmonic of the vacuum tube oscillator is very high and is by-passed through the condensers 40 and 41 which offer very low impedance to high frequencies. These condensers serve also to by-pass any components of the crystal frequency itself, the fundamental frequency of the vacuum tube oscillator, and the sum and difference frequencies of the crystal and the vacuum tube oscillator fundamental which may appear in the cathode resistor circuits of the mixer tubes 12 and 13. Thus so far as the resistors 35 and 36 are concerned, only the difference frequency of the crystal oscillator and the tenth harmonic of the vacuum tube oscillator need be considered. Currents of this difference frequency flow through the two output circuits of the tubes 12 and 13 from the positive terminal of the battery 34 through separate halves of the primary winding of the transformer 14 in opposite directions to the anodes of the tubes 12 and 13, and through the tubes 12 and 13 and the resistors 35 and 36 to ground and the negative terminal of the battery 34. Thus if the resistors 35 and 36 are of equal resistance, the capacitors 40 and 41 of equal capacitance, and the tubes 12 and 13 of similar electrical characteristics, the same average direct current potential exists at the electrically spaced positive terminals 55 and 56 of the resistors 35 and 36, respectively. Under these conditions the input terminals of the signal amplifier 44 are supplied with the same potential,

and the output of the amplifier is zero, so that no signal indication is discernible either through the headphone 45 or the visual tuning indicator 46.

Let it now be assumed that the frequency of the vacuum tube oscillator 11 changes slightly so that the tenth harmonic of the new frequency is no longer the same as the fixed frequency of the crystal source 10. Referring now to Fig. 2, I have shown a group of diagrams illustrating the grid voltages of the mixer tubes 12 and 13 under this condition. In this diagram the curve E_{16} represents the voltage from the source 10 applied to the control grid 16 of the electric discharge tube 12, and the curve E_{17} represents the same voltage applied to the control grid 17 of the discharge tube 13. It will be noted that these voltages are identical in phase and magnitude. For the purpose of illustration a frequency of four cycles per second has been assumed for E_{16} and E_{17} and for the normal value of the tenth harmonic from the source 11. If it is assumed now that the tenth harmonic of the vacuum tube oscillator 11 has changed to three cycles per second, it will be evident that the curve E_{16} represents the voltage of the suppresser grid 19 in the tube 12, while the voltage E_{20} represents the voltage simultaneously applied to the suppresser grid 20 in the tube 13. It will be noted that these voltages are in phase opposition. Since the suppresser grid and control grid characteristics of the tubes 12 and 13 are qualitatively similar, the current controlling effect of separate voltages on these grids is similar to the effect of the sum of the voltages upon a single grid. Thus the equivalent grid voltage supplied to the mixer tube 12 is the sum of E_{19} and E_{16} . This voltage has been illustrated by the curve E_{12} . Similarly, the curve E_{13} represents the equivalent grid voltage applied to the mixer tube 13. It will be noted that these net grid voltages vary in magnitude in like manner but in opposite phase as a result of beating together the identical voltages E_{16} and E_{17} with the oppositely phased voltages E_{19} and E_{20} .

Referring now to Fig. 3, I have shown a representative grid characteristic curve E_g which is qualitatively similar to the characteristic of both the control grids and the suppresser grids of the mixer tubes 12 and 13 and represents the characteristic of an assumed equivalent single grid in each tube. It will be understood that the assumption of an equivalent grid has been made merely in the interest of simple qualitative explanation, and that the operation is subject to more precise analysis. It is well known that the lower portion of the curve E_g is nonlinear and that if the average grid bias is maintained in this region of the curve, the tubes 12 and 13 function as detectors. I have shown a line E_{gb} which represents the average negative grid bias resulting from the connection of the resistors 35 and 36 between the cathodes and control grids of the tubes 12 and 13. Upon the line E_{gb} I have drawn the grid voltage curves E_{12} and E_{13} taken from Fig. 2. It will now be clear to those skilled in the art that due to the grid characteristic of the tubes 12 and 13 as illustrated by the curve E_g , the anode current of the tube 12 is represented by the curve I_{12} , while the anode current of the tube 13 is represented by the curve I_{13} . Now it may be readily observed that due to the nonlinearity of the curve E_g the positive half-cycles of the curves I_{12} and I_{13} are considerably more amplified than are the negative half-cycles, so that the average of the curve I_{12} is represented by a curve I_{35} , and the average of

the current I_{13} is represented by a curve I_{36} . The curves I_{35} and I_{36} represent average instantaneous unidirectional currents in the resistors 35 and 36, respectively. Currents of the frequency of I_{12} and I_{13} are by-passed around the resistors 35 and 36 through the condensers 40 and 41.

From Figs. 2 and 3 it will now be understood that when the tenth harmonic of the tube oscillator 11 is not of the same frequency as the output of the crystal oscillator 10, the unidirectional potential of the points 55 and 56 in the output circuits of the tubes 12 and 13, respectively, varies in opposite phase at the difference frequency between that of the source 10 and that of the tenth harmonic of the source 11. It will also be clear from Figs. 2 and 3 that where the difference frequency is zero the voltages E_{12} and E_{13} will be sinusoidal and I_{35} and I_{36} will be constant and equal. In the example assumed at Figs. 2 and 3 the difference frequency is one cycle per second, so that a signal potential of one cycle per second is applied to the signal amplifier 44 where it is amplified and supplied to both the audible signal reproducing device 45 and the visual signal reproducing device 46. A signal frequency of only one cycle per second will not be discernible through the headphone 45. In this instance the signal will be very easily detectable in the visual tuning indicator 46.

It will be understood that the difference frequency determined by the fixed frequency of the source 10 and the selected harmonic of the source 11 may vary over a wide range. It is for this reason that both an audible and visual signal reproducer is provided in the output of the signal amplifier 44. For example, if the difference frequency producing the signal indication is relatively high, for example, of the order of a hundred cycles per second, it is very difficult to discern upon the visual indicator 46 but is easily detectable upon the audible indicator 45. Thus by using the headphone 45 an operator may adjust the frequency of the vacuum tube oscillator 11, so that the signal frequency is gradually reduced to the point where it is no longer audible. At this point the signal frequency will be sufficiently low, so that it will be discernible upon the visual tuning indicator 46, and by now using the visual tuning indicator the operator may continue to reduce the signal frequency to zero. In this manner the frequency of the vacuum tube oscillator 11 may be readily adjusted to a predetermined value by means of the fixed frequency of the source 10, and the intermediate output frequency at the transformer 14 maintained at a desired value.

While I have described only one preferred embodiment of my invention by way of illustration, many further modifications will occur to those skilled in the art, and I therefore wish to have it understood that I intend in the appended claims to cover all such modifications as fall within the true spirit and scope of my invention.

What I claim as new and desire to secure by Letters Patent of the United States is:

1. The method of maintaining constant the frequency of electric oscillations comprising beating electric oscillations of a predetermined normal fundamental frequency, subject to variation with electric oscillations at a fixed frequency which is an integral multiple of said fundamental frequency to obtain oscillatory output energy at first sum and difference frequencies, beating said oscillations of fixed frequency with one phase of a harmonic oscillation of said fundamental fre-

quency having a frequency normally substantially equal to said fixed frequency to obtain oscillations at second sum and difference frequencies, beating said oscillations of fixed frequency with the opposite phase of said harmonic oscillations to obtain oscillations of opposite phase at said second sum and difference frequencies, deriving a signal indication from said oscillations of opposite phase at said second difference frequency, and adjusting said fundamental frequency to maintain said signal indication fixed.

2. In combination, a pair of electric discharge devices having current control elements, balanced output circuits for said discharge devices connected in opposing relation, each of said output circuits including a resistor, said resistors being of substantially the same resistance and each having one end connected to a common portion of said output circuits, a first source of electric oscillations having points of like potential connected to a current control element of each of said electric discharge devices, a second source of electric oscillations having points of opposite potential connected to a current control element of each of said electric discharge devices, the frequency of one of said oscillations being fixed and the frequency of a predetermined harmonic of the other of said oscillations being normally substantially equal to said fixed frequency, energy translating means in said output circuits responsive to the difference of said fixed frequency and the fundamental of said harmonic frequency, and signal reproducing means connected to electrically spaced points of normally equal potential upon said resistors for response in accordance with a difference of frequency between said fixed frequency and said harmonic frequency, whereby by maintaining a null signal the output of said energy translating means may be maintained at a predetermined frequency.

3. In combination, a pair of electric discharge devices having current control electrodes, balanced output circuits for said discharge devices connected in opposing relation, each of said output circuits including a resistor, said resistors being of substantially the same resistance and each having one end connected to a common portion of said output circuit, a source of electric oscillations of substantially constant frequency having points of like potential connected to a current control electrode of each of said electric discharge devices, a second source of electric

oscillations of variable frequency having points of opposite potential connected to a current control electrode of each of said electric discharge devices, said fixed frequency being an integral multiple of the normal fundamental of said variable frequency, energy translating means in said output circuits responsive to the difference of said fixed frequency and said fundamental frequency, and signal reproducing means connected across at least a portion of each of said resistors to points of normally equal potential for response in accordance with a difference of frequency between said fixed frequency and a predetermined harmonic of said variable frequency, whereby by maintaining a fixed signal the output of said energy translating means may be maintained at a predetermined frequency.

4. In combination, a pair of electric discharge devices having current control electrodes, balanced output circuits for said discharge devices connected in opposing relation, each of said output circuits including a resistor, said resistors being of substantially the same resistance and each having one end connected to a common portion of said output circuits, a first source of electric oscillations having points of like potential connected to a current control electrode of each of said electric discharge devices, a second source of electric oscillations having points of opposite potential connected to a current control electrode of each of said electric discharge devices, the frequency of one of said oscillations being fixed and the frequency of a predetermined harmonic of the other of said oscillations being normally substantially equal to said fixed frequency, energy translating means in said output circuits responsive to the difference of said fixed frequency and the fundamental of said harmonic frequency, a signal amplifier connected across at least a portion of each of said resistors to points of normally equal potential, and visual and audible signal reproducing means connected to said signal amplifier for simultaneous response in accordance with a difference of frequency between said fixed frequency and said harmonic frequency, whereby said audible signal means is effective upon a large difference frequency and said visual signal means is effective upon a relatively small frequency difference so that said frequency difference may be adjusted substantially to zero to maintain the output of said energy translating means at a predetermined frequency.

HOWARD M. CROSBY.
